UNITED STATES PATENT OFFICE.

JOHN SPRINGER AND WILLIAM A. ROBBINS, OF TRENTON, NEW JERSEY.

ROTARY ENGINE.

SPECIFICATION forming part of Letters Patent No. 716,589, dated December 23, 1902.

Application filed December 14, 1901. Serial No. 85,885. (No model.)

To all whom it may concern:

Be it known that we, JOHN SPRINGER and WILLIAM A. ROBBINS, citizens of the United States, residing at Trenton, in the county of Mercer and State of New Jersey, have invented certain new and useful Improvements in Rotary Engines, of which the following is a specification.

This invention relates to rotary engines, and has for its object to provide an engine of this character of simple construction and increased efficiency.

Another object of the invention is to provide an engine of this character wherein there will be a continuous exertion of pressure upon the driving-shaft.

Another object of the invention is to provide a rotary engine having no dead-center.

Another object of the invention is to provide an improved valve for a cut-off.

Another object of the invention is to provide an improved governor-controlled cut-off for rotary engines; and another object of the invention is to provide an improved piston-wheel for rotary engines.

In the drawings accompanying and forming a part of this specification, Figure 1 is a vertical central longitudinal section of a form of our invention; and Fig. 2 is a sectional view, at right angles to Fig. 1, taken on the line *a a* thereof. Fig. 3 is a perspective view of a form of valve. Fig. 4 is a diagram of the valve-port. Fig. 5 is a perspective of one of the piston-wheels and associated parts. Figs. 6, 7, and 8 are diagrammatic views on the plane of Fig. 2, but to a smaller scale, showing the operation of the parts.

The engine is shown as mounted upon a suitable bed, (designated in a general way by A,) to which is secured a suitable housing (designated in a general way by B) and which is shown as embodying end plates 7 8 and a central plate 9, substantially parallel with the end plates, to which plates are secured rings 10 11, constituting housings and expansion-chambers for the piston-wheels 11 11, which wheels are rigidly mounted upon a driving-shaft 12, having suitable bearings 13 in housings 14, secured to the end plates, shown as 50 conoidal in form and having the journals in the apexes. Each wheel is shown as pro-

vided with two pistons 15, freely sliding in chambers 16, (shown as tangential,) each of which chambers is in communication by means of an inlet-port 17 with a valve 18, located in a chamber 19 in the piston-wheel and affording access to a centrally-located fluid-chest 20, receiving its fluid from the source of supply through the port 21. The fluid-chest 20 is shown as located between the piston-wheels. Connected with the inner end of each of the piston-chambers is a channel 22, communicating with the perimeter of the wheel immediately behind the piston. Two concentric expansion-chambers (designated in a general way by C C') are shown as provided between the perimeter 11' of each of the piston-wheels and the inner perimeter 10' of the housing 10, which are shown as having diametrically oppositely disposed exhaust-ports 23 23, communicating with some suitable point outside of the housing. At a short distance ahead of the exhaust-port an incline 24 is provided upon the housing 10, upon which inclines the pistons ride up and are 75 pressed into the piston-chambers, whereupon they will cut off or throttle the channel 22, and immediately thereafter the pistons will ride past the exhaust-ports and permit the cylinder to exhaust, a portion 25 of the face of the 80 housing immediately past the exhaust-port being in engagement with the piston-wheel, thus bringing the piston completely within the wheel at that point. An inclined plane or face 26 leads away from such point of engagement, permitting the piston to slide out from its chamber under the pressure exerted upon its upper end, it being held constantly against the outer working face of the expansion-chamber by such pressure. The incline 90 26 may, if desired, be made more abrupt than the incline 24. The inclines 24 and 26 and face 25 form a cam-face. Upon the piston being pushed down by the fluid expansion the fluid may pass through the channel 22 and exert its expansive pressure upon the piston, expanding between the piston and the face 26, which takes the place of a cylinder-head. It will be seen that the piston not only acts as a piston, but also as a cut-off or 95 throttle. The fluid in the piston thereby is prevented from escape; otherwise the fluid

back of the piston would exhaust and the incoming fluid would expand unnecessarily, causing a waste.

The valves 18 are shown as each composed of a hollow cylinder 27, open at one end 28 and provided at the perimeter with a triangular opening 29, a diagram thereof being shown in Fig. 4, having one side 30 parallel to the axis of the cylinder and one side 31 substantially transverse thereto, which opening leads from the outside into the hollow interior 32, the open end of the cylinder being in communication with the fluid-chest 20 and forming an inlet-port, the organization being such that the side 30 of the triangle will coincide with the side of the inlet-port 17 for the piston. The valves are shown as provided with stems 32', passing through suitable adjustable stuffing-boxes 33 and glands 36, having packing 37 therebetween. The valve-stems are provided with journals 37', having bearings 38 on wings 39 of a collar 40. The driving-shaft journals are shown as provided with bushings 41, secured in the housing by set-screws 42, each bushing extending inwardly in the form of a sleeve 43, upon which sleeve a gear-wheel 45 is loosely mounted and capable of reciprocation thereon. The gear-wheel is provided with a hub or sleeve 45', upon which is freely mounted a collar 40, held from reciprocation on the sleeve 45' by a ring 46', held in place on the sleeve or hub by set-screws. Each valve-stem is provided with a pinion 46, in mesh with the gear-wheel 45, the organization being such that upon the revolution of the piston-wheels and shaft the pinions will be rotated by the stationary gear-wheel and rotate the valves, and the openings in the valves and valve-chambers will be caused to register to form ports and on further rotation to cut off. In Fig. 5 the upper valve is shown in a position relatively to the opening in its chamber to produce a full-sized port, the position of the piston being shown at the beginning of its stroke. The fluid will be gradually cut off by means of the spiral conformation of the port of the valve, so that upon the completion or approach to completion of the stroke of the piston the fluid will be entirely cut off.

The ring 46' may be engaged by points 48 of a yoke 49, which yoke is secured upon a rock-shaft 50, projecting out through the housing to either a governor or some other suitable operating device. If the engine is running too fast, upon the rocking of the shaft a predetermined distance the yoke will be moved, thereby moving the valves in a direction from the stuffing-boxes and will thereby diminish the area of the ports formed by the openings in the valves and the openings in the chambers and cause the valves to cut off sooner. Upon the reduction of speed the valves will be moved back toward their full port and normal cut-off position. Each side of the piston-wheels is shown as provided with suitable annular channels 51, in which suit-

able packing material 52 may be lodged. The pistons upon the respective wheels are shown as placed at ninety degrees, thus obviating dead-centers.

A channel 53 may be provided on the face 25, and suitable packing material 54 may be applied thereto.

The housing is shown as incased in suitable non-conducting material 55.

Having described our invention, we claim—

1. A rotary engine embodying pistons; an induction-port for each piston; a plurality of means for independently throttling each induction-port; expansion-chambers; and a cam-face in each expansion-chamber effective to actuate one of the throttling means.

2. In a rotary engine, the combination of framework; a shaft carried thereby; a plurality of piston-wheels mounted upon the shaft independently of each other; an expansion-chamber for each piston-wheel; a fluid-chest common to the piston-wheels; and a valve and valve-chamber carried by each wheel, the valve and valve mechanism of one wheel being independent of and separate from the other wheel.

3. In a rotary engine, the combination of framework; a shaft carried thereby; a plurality of piston-wheels independently mounted upon the shaft; an expansion-chamber for each piston-wheel; a fluid-chest common to the piston-wheels; a valve carried by each wheel for its piston; and means outside of each piston-wheel independent of the other wheel and its valve effective to operate the valve of each wheel independently of the valve of the other wheel.

4. In a rotary engine, the combination of a framework; a shaft carried thereby; a plurality of piston-wheels mounted upon the shaft; a plurality of pistons carried by each wheel; an expansion-chamber for each piston-wheel; a fluid-chest common to the piston-wheels; valves carried by each piston-wheel for opening and cutting off the fluid to each piston; and means outside of the piston-wheels effective to operate the valves to open and cut off, and to regulate the area of opening and instant of cut off.

5. In a rotary engine, the combination with an expansion-chamber, of a piston-wheel; a plurality of pistons carried thereby and operable in the same expansion-chamber; valves effective upon rotation to admit steam to the pistons and upon further rotation to cut off; means outside thereof for operating the valves by the movement of the piston-wheel and comprising a gear-wheel connected to each valve; and a gear-wheel fixed against rotation in mesh therewith.

6. The combination with a shaft; a piston-wheel; a piston carried thereby; a valve effective upon rotation to admit steam behind the piston and upon further rotation to cut off, and upon reciprocation effective to regulate the cut off; a valve-stem protruding from the valve; a stationary gear-wheel surround-

ing the shaft; a sleeve or hub on the gear-wheel; a collar on the sleeve and in which said valve-stem is journaled; and a pinion on the valve-stem in mesh with the gear-wheel 5 and effective upon the rotation of the piston-wheel to rotate the valve.

7. The combination with a shaft; a piston-wheel; a piston carried thereby; a valve effective upon rotation to admit steam behind 10 the piston and upon further rotation to cut off, and upon reciprocation effective to regulate the cut off; a valve-stem protruding from the valve; a stationary gear-wheel surrounding the shaft; a hub or sleeve on the gear-wheel; a collar on the sleeve in which said valve-stem is journaled; a pinion on the valve-stem in mesh with the gear-wheel and effective upon the rotation of the piston-wheel 15 to rotate the valve; and means connected with a governor effective to shift the collar and reciprocate the valve.

8. The combination with a shaft; a piston-wheel; a piston carried thereby; a valve effective upon rotation to admit steam behind 20 the piston and upon further rotation to cut off, and upon reciprocation effective to regulate the cut off, a valve-stem protruding from the valve; a collar on the shaft in which said valve-stem is journaled; a stationary gear-wheel surrounding the shaft; and a pinion on the valve-stem in mesh therewith and effective upon the rotation of the piston-wheel to 25 rotate the valve, a hub on the gear-wheel; a rock-shaft; and a yoke carried by the rock-shaft; and in engagement with the hub and 30 capable of reciprocating the collar, valve and gears.

9. The combination with a housing, of a driving-shaft therein; a piston-wheel located 40 upon the shaft; an expansion-chamber between the perimeters of the piston-wheel and housing; exhaust-ports for the expansion-chamber; inclined faces before and behind each exhaust-port; piston-chambers in the 45 piston-wheel; an inlet-port leading from the interior of the piston-wheel to the piston-chamber and from the piston-chamber to the perimeter of the wheel; pistons located in the piston-chambers and capable of movement in 50 and out under the influence of the inclined faces and of pressure of the expansion fluid respectively and capable upon their inward movement of cutting off a portion of the inlet, at all times leaving the portion of such inlet 55 between the piston-chamber and the perimeter exposed to the exhaust.

10. In a rotary engine, the combination with a housing of a shaft journaled in the housing; a piston-wheel mounted upon the shaft and 60 having its perimeter concentric to the perimeter of the housing, an expansion-chamber formed by the space therebetween; an exhaust-port leading from the expansion-chamber; an inclined face at the approach to the 65 exhaust-port; a piston-chamber in the piston-wheel; an inlet-port from the piston-chamber to the perimeter of the piston-wheel; a

piston in the piston-chamber and capable of moving thereout under the influence of pressure and capable upon such movement of 70 opening the inlet-port, and upon contact with the inclined face of the exhaust-port, of movement into the piston-wheel, and upon such movement capable of throttling the inlet-port; a cylindrical valve-chamber, in the piston-wheel and having its axis parallel to the axis of the wheel; a rotary and reciprocatory valve, located in the valve-chamber, comprised of a hollow cylindrical body having a closed end and an inlet-port comprising an open end 75 thereof; a port in the perimeter of the valve, communicating with the inlet-port; a fluid-chest located adjacent thereto and in communication with the valve through its inlet-port; an opening in the perimeter of the valve-chamber in communication with the piston-chamber and capable upon registry with the opening in the perimeter of the valve, upon rotation thereof, to form a port, and capable 80 upon the reciprocation of the valve to vary 85 the area of the port; a valve-stem projecting from the closed end of the valve; a pinion and a journal thereon; a stationary bushing in the journal of the shaft; a gear-wheel on the bushing and in gear with the pinion; a hub 90 or sleeve on the gear-wheel; a collar loosely mounted on the hub and capable of rotation thereon; a journal on said collar, in which the valve-stem journal is entered; a connection between the gear-wheel and collar effective 95 to cause the same to reciprocate together; a rock-shaft located adjacent thereto; and a yoke carried by the rock-shaft and in engagement with the hub.

11. In a rotary engine, the combination with 105 a housing, comprising a substantially cylindrical portion, and end portions conoidal in form; of a shaft journaled in the apexes of the conoidal portions; piston-wheels concentrically mounted upon the shaft, and having 110 their perimeters concentric to the inner perimeter of the housing; expansion-chambers formed by the spaces between the perimeters of the respective piston-wheels and housing; exhaust-ports leading from each expansion-chamber; inclined faces at each side of the 115 exhaust-ports; piston-chambers in the piston-wheels; an inlet-port from each piston-chamber to the perimeter of the piston-wheel; pistons in the piston-chambers, and capable of 120 movement thereout under the influence of pressure, and capable upon such movement of opening the inlet-ports, and upon contact with the inclined faces adjacent to the exhaust-ports of movement into the piston-wheels and upon such movement capable of 125 throttling the inlet-ports; cylindrical valve-chambers in the piston-wheels, having their axes parallel to the axis of the shaft; reciprocatory and rotary valves located in the 130 valve-chambers, each comprised of a hollow cylindrical body having a closed end and an inlet-port comprising an open end thereof, a port in the perimeter of the valve communi-

cating with the inlet-port through the interior of the cylinder; a fluid-chest located between the piston-wheels and in constant communication with the interior of the valves 5 through their inlet-ports; openings in the perimeters of the valve-chambers in communication with the piston-chambers and capable upon registry with the openings in the perimeters of the valves upon the rotation 10 thereof to form ports and capable upon the reciprocation of the valves to vary the area of the ports; valve-stems projecting from the closed ends of the valves; a pinion and a journal on each stem; stationary bushings for each 15 piston-wheel in the journal of the shaft, a gear-wheel on each bushing and in gear with the pinions of the valve-stems; a collar loosely mounted on the shaft adjacent to each gear-wheel, capable of rotation thereon and reciprocation therewith; journals on said collars; journals on each of the valve-stems; connections between the gear-wheels and collars on the respective bushing effective to cause the collar and gear-wheel to reciprocate together; 20 and rock-shafts adjacent thereto; yokes carried on the rock-shafts and in engagement with the gear-wheels.

12. The combination with an expansion-chamber; a piston-wheel located therein; a 30 piston-chamber in the piston-wheel; a port extending through the piston-chamber to the expansion chamber; a chest; a valve between the chest and port; means for operating the valve; and a piston in the piston-chamber, 35 capable of movement therein under the influence of pressure and upon such movement coöperative with the valve to control the port.

13. The combination with a source of expansible-fluid supply, of an expansion-chamber; a cam-face therein; a piston-wheel 40 mounted in the expansion-chamber; a piston-chamber in the wheel; a port extending through the piston-chamber to the expansion-chamber; a chest; a valve between the chest 45 and port; means for actuating the valve upon the rotation of the wheel; and a piston in the piston-chamber, capable of movement into the expansion-chamber under the influence of the pressure of the fluid and by such movement effective to open the port with the co-operation of the valve, and capable of movement into the piston-wheel upon engagement with the cam-face and by such movement effective to throttle the port irrespective of the 55 valve.

14. A rotary piston-wheel and a rotary cut-off valve carried thereby and capable of continuous rotation in the direction of rotation of the piston-wheel.

60 15. A rotary piston-wheel and a rotary cut-off valve carried thereby capable of continuous rotation in the direction of rotation of the piston-wheel and at a different speed.

16. In a rotary engine, the combination of 65 an expansion-chamber; a plurality of cams constituting heads for the chamber, a rotary piston-wheel, two or more pistons carried

thereby, a rotary cut-off valve carried by the piston-wheel for each piston; and means for rotating the valves in the direction of rotation of the piston-wheel, a number of times at each rotation thereof equal to the number of cams. 70

17. A piston-wheel for a rotary engine comprising a cylindrical body having piston-chambers disposed at an angle to the radius; a valve-chamber located therein; a valve in the valve-chamber; a channel leading from the valve-chamber to the piston-chamber; and a port leading from the piston-chamber 80 to the perimeter of the wheel. 75

18. The combination with a shaft; a piston-wheel; a piston carried thereby; a rotary valve carried by the piston-wheel and effective upon rotation to admit steam behind the piston and upon further rotation to cut off and upon reciprocation effective to regulate the cut off; and means for rotating the valve and for reciprocating the same. 85

19. In an engine, the combination with a 90 piston-wheel; a piston carried thereby; a valve-chamber in the piston-wheel having an opening for supplying fluid behind the piston; a rotary and reciprocatory valve having an opening of a different shape than the opening 95 in the valve-chamber, said opening effective upon the rotation of the valve and upon the registry thereof to establish a port and upon further rotation to cut off and upon reciprocation to regulate the instant of cut off; means for rotating the valve; and means for reciprocating the valve. 100

20. In an engine, the combination with a piston-wheel; a plurality of pistons carried thereby; inlet-ports for each piston; a valve-chamber for each piston and each having an opening connected with its port; a rotary and reciprocatory valve within each valve-chamber provided with an opening, said opening effective upon the rotation of the valve and 105 upon registry thereof with the opening in the chamber to establish a port and upon further rotation to cut off and upon reciprocation to regulate the instant of cut off; means for rotating the valves; and independent means for reciprocating the valves. 110

21. In an engine, the combination with a rotary piston-wheel; a plurality of pistons located therein at an angle to the radius thereof inclined away from such radius in the direction of rotation; an independent valve and valve-chamber for each piston; and an expansion-chamber surrounding the piston-wheel and provided with cams constituting abutments in the nature of heads for the expansion-chamber. 120

22. In a rotary engine, the combination with a piston-wheel; a substantially cylindrical chamber surrounding the wheel; a plurality of pistons carried thereby and capable of 125 movement in and out of the wheel; an abutment in the nature of a head, within the chamber, of gradual ascent and of precipitate declivity; a valve-chamber for supplying fluid 130

behind each piston; an opening in the valve-chamber; a valve within each chamber provided with an opening capable upon rotation to open a port and to cut off, and upon reciprocation to vary the area of the port and the instant of cut off; means connecting all the valves for rotation with the rotation of the piston-wheel; a governor; and means connecting all the valves for operation in unison by the governor.

23. In a rotary engine, the combination with a piston-wheel; a piston located therein; a valve-chamber; a rotary and reciprocatory valve located in the chamber for controlling the supply of fluid behind the piston; an opening in the valve-chamber; an opening in the valve having a portion of the same size and shape as the opening in the valve-chamber and a portion of less dimension in one direction than the opening in the valve-chamber; and means for rotating and for reciprocating the valve.

24. In a rotary engine, the combination with a piston-wheel; a piston located therein; a valve-chamber; a rotary and reciprocatory valve for supplying fluid behind the piston located in the valve-chamber; an opening in the valve-chamber; an opening in the valve having a portion of the same size and shape as the opening in the chamber and a portion of less dimension in one direction than the opening in the valve-chamber; means operable in the direction of such decrease in dimension for rotating the valve; and means for reciprocating the valve.

25. In a rotary engine, the combination with a piston-wheel; an expansion-chamber surrounding the wheel; an exhaust-port from the expansion-chamber; an abutment in the nature of a head at the region of the exhaust, being of gradual ascent upon the approach side and of precipitate declivity upon the recession side; a piston-chamber in the wheel disposed at an angle to the radius thereof; a piston within the piston-chamber and capable of movement into and out of the wheel; a port for supplying expansion fluid behind the piston; a valve-chamber having an opening communicating with the port; a valve located within the chamber provided with an opening capable of registry with the opening in the chamber and having a portion of such opening of the same size and shape as the opening in the chamber and a portion of less dimension in one direction than the opening in the valve-chamber and gradually decreasing in such dimension; and means for shifting the valve to bring the respective portions of its opening into registry with the opening in the valve-chamber for the purpose of establishing a port and to cut off.

26. In a rotary engine, the combination with a piston; a port for supplying expansion fluid behind the piston; a valve-chamber having an opening communicating with the port; a valve located within the chamber provided with an opening capable of registry with the

opening in the chamber and having a portion of such opening of the same size and shape as the opening in the chamber and a portion of less dimension in one direction than the opening in the valve-chamber and gradually decreasing in such dimension; and means for shifting the valve to bring the respective portions of its opening into registry with the opening in the valve-chamber for the purpose of establishing a port and to cut off.

27. In a rotary engine, the combination with a piston; a port for supplying expansion fluid behind the piston; a valve-chamber having an opening communicating with the port; a valve located within the chamber provided with an opening capable of registry with the opening in the chamber and having a portion of such opening of the same size and shape as the opening in the chamber and a portion of less dimension in one direction than the opening in the valve-chamber and gradually decreasing in such dimension; means for rotating the valve to bring the respective portions of its opening into registry with the opening in the valve-chamber for the purpose of establishing a port and to cut off; and means for reciprocating the valve to vary the area of port and the instant of cut off.

28. In a rotary engine, the combination with a piston-wheel; an expansion-chamber surrounding the wheel; an exhaust-port for the expansion-chamber; an abutment in the nature of a head at the region of the exhaust, being of gradual ascent upon the approach side and of precipitate declivity upon the recession side; a piston-chamber in the wheel disposed at an angle to the radius thereof; a piston within the piston-chamber and capable of movement into and out of the wheel; a port for supplying expansion fluid behind the piston; a valve-chamber having an opening communicating with the port; a valve located within the chamber provided with an opening capable of registry with the opening in the chamber and having a portion of such opening of the same size and shape as the opening in the chamber and a portion of less dimension in one direction than the opening in the valve-chamber and gradually decreasing in such dimension; means for rotating the valve to bring the respective portions of its opening into registry with the opening in the valve-chamber for the purpose of establishing a port and to cut off; and means for reciprocating the valve to vary the area of port and the instant of cut off.

29. In a rotary engine, the combination with a piston-wheel; a cylindrical expansion-chamber surrounding the piston-wheel; an exhaust-port from the chamber; a piston-chamber within the piston-wheel at an angle to the radius thereof and projecting toward the direction of rotation of the wheel; a valve-chamber within the piston-wheel; a passage therefrom to the perimeter of the wheel embracing in part a portion of the piston-chamber; a piston located within the chamber and ca-

pable of reciprocation therein; and an abutment in the nature of a head within the chamber adapted for engaging the piston and forcing the same into the piston-chamber and 5 upon the approach side thereof having a gradual ascent and upon the recession side thereof a precipitate descent.

30. In a rotary engine, the combination with a piston-wheel; an expansion-chamber surrounding the wheel; exhaust-ports from the chamber; pistons located within the piston-wheel at an angle to the radius thereof and inclining toward the direction of rotation of the wheel and capable of movement into and 10 out of the wheel; a valve and valve-chamber carried by the wheel for each piston; an inclined face of gradual ascent upon the approach to each port; and an inclined face of precipitate declivity upon the recession side 15 thereof.

31. In a rotary engine, the combination with a piston-wheel; a cylindrical expansion-chamber surrounding the wheel; exhaust-ports for the chamber; pistons located within the piston-wheel at an angle to the radius thereof and inclined toward the direction of the rotation thereof, and capable of movement into and out of the wheel; an inclined face of gradual ascent upon the approach to each port; 25 an incline of precipitate declivity upon the recession side thereof; and rotary valves carried by the wheel for supplying expansion fluid behind each piston.

32. In a rotary engine, the combination with a piston-wheel; a piston-chamber surrounding the wheel; exhaust-ports for the chamber; pistons located within the piston-wheel at an angle to the radius thereof and inclined toward the direction of the rotation of the 35 wheel and capable of movement into and out 40

of the wheel; an inclined face of gradual ascent upon the approach to each port; an incline of precipitate declivity upon the recession side thereof; an inlet-port for supplying expansion fluid behind each piston; a valve-chamber in the wheel having an opening in communication with the port; a valve located within each valve-chamber; an opening in the valve for registering with the opening in the valve-chamber; and means for rotating the valve operable by the rotation of the piston-wheel. 45

33. In a rotary engine, the combination with a piston-wheel; a piston-chamber surrounding the wheel; exhaust-ports for the chamber; pistons located within the piston-wheel at an angle to the radius thereof and inclined toward the direction of the rotation of the wheel and capable of movement into and out of the wheel; an inclined face of gradual ascent upon the approach to each port; an incline of precipitate declivity upon the recession side thereof; an inlet-port for supplying expansion fluid behind each piston; a valve-chamber having an opening in communication with the port; a valve located within each valve-chamber; an opening in the valve for registering with the opening in the valve-chamber having a portion of such opening of the same shape and area as the opening in the valve-chamber and a portion of gradually-decreasing area; means controlled by the rotation of the wheel for rotating the valves in unison; and means for reciprocating the valves in unison. 55 60 65 70
